[57] CLAIM

The ornamental design for a portable communication device, as shown and described.

DESCRIPTION

FIG. 1 is a front elevational view of a portable communication device showing our new design thereof in an open position;

FIG. 2 is a rear elevational view thereof;

FIG. 3 is a top plan view thereof;

FIG. 4 is a bottom plan view thereof;

FIG. 5 is a right side elevational view thereof;

FIG. 6 is a left side elevational view thereof;

FIG. 7 is an isometric view thereof;

FIG. 8 is a front elevational view showing the portable communication device in a closed position;

FIG. 9 is a rear elevational view thereof;

FIG. 10 is a top plan view thereof;

FIG. 11 is a bottom plan view thereof;

FIG. 12 is a right side elevational view thereof;

FIG. 13 is a left side elevational view thereof; and,

FIG. 14 is an isometric view thereof.

The broken lines showing the portable communication device display portion in FIGS. 1, 7-8 and 14 are for illustrative purposes only and form no part of the claimed design.
